ATTORNEY.

UNITED STATES PATENT OFFICE

135,155

DESIGN FOR A FLEXIBLE SANDAL

Basil D. Huff, New York, N. Y.

Application January 23, 1943, Serial No. 109,334

Term of patent 7 years

To all whom it may concern:

Be it known that I, Basil D. Huff, a citizen of the United States of America, residing in New York city, county of New York, and State of New York, have invented a new, original, and ornamental Design for a Flexible Sandal, of which the following is a specification, reference being had to the accompanying drawing, forming part thereof.

Fig. 1 is a front perspective view of a flexible sandal showing my new design.

Fig. 2 is bottom perspective view thereof.

I claim:

The ornamental design for a flexible sandal, substantially as shown.

BASIL D. HUFF.
